Henry E. Smith, Troy, N. Y., assignor to Parks &
Parks, Inc., Troy, N. Y.

Application February 11, 1935, Serial No. 55,344

Term of patent 14 years

To all whom it may concern:

Be it known that I, Henry E. Smith, a citizen of the United States, residing at Troy, in the county of Rensselaer and State of New York, have invented a new, original, and ornamental Design for a Dauber, of which the following is a specification, reference being had to the accompanying drawing, forming part thereof.

Figure 1 is a top plan view of a dauber showing my new design.

Figure 2 is a side elevation thereof.

Figure 3 is an end elevation.

Figure 4 is a section on line 4—4, Figure 2.

I claim:

The ornamental design for a dauber, as shown.

HENRY E. SMITH.
